UNITED STATES PATENT OFFICE

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA

FLOW CONTROLLING SYSTEM

Application filed December 5, 1928. Serial No. 323,931.

This invention relates to improvements in fire extinguishing apparatus, and relates more particularly to improvements in means for releasing and controlling the flow of the fire extinguishing agencies.

5 The principal object of the invention is to provide a novel and improved device operative under predetermined temperature conditions for releasing a fire extinguishing agent.

10 More specifically, an object of the invention is to provide a device of the aforesaid character which shall be extremely sensitive and positive in operation and which will not be adversely affected by changing conditions of atmosphere and temperature and which will not deteriorate over long periods of time.

15 Another object of the invention is to provide in conjunction with a device of the aforesaid character novel apparatus adapted for generating and releasing a fire extinguishing foam.

20 To this general end, the invention resides in part in the provision of novel apparatus for releasing a foam-forming medium and for interrupting the flow of said medium after a predetermined period.

25 The invention further resides in certain novel and useful structural and mechanical details hereinafter set forth and illustrated in the attached drawings, in which:

30 Figure 1 is a general assembly view of apparatus made in accordance with my invention;

35 Fig. 2 shows in vertical section the release box and valve mechanisms forming a part of the apparatus;

40 Fig. 3 is a front elevation of the release box and immediately associated valve parts as shown in Fig. 2;

45 Fig. 4 is a front view of the release box with the cover removed showing some of the interior working parts;

50 Fig. 5 is a sectional view similar to Fig. 2 but showing the parts in the released position;

55 Fig. 6 is a front elevation of the release box and the associated parts as shown in Fig. 5;

60 Fig. 7 is a section on the line 7—7, Fig. 6;

Fig. 8 is a section on the line 8—8, Fig. 5;

Fig. 9 is a plan view of the thermosensitive device constituting one of the prime actuators of the release mechanism illustrated in Figs. 2 to 6;

55 Fig. 10 is a section on the line 10—10, Fig. 9; and

Fig. 11 is a side elevational view of the valve on the line 10—10, Fig. 9.

With reference to the drawings, the apparatus illustrated comprises a tank 1 which constitutes a mixing chamber for foam-forming chemicals, the foam constituting in the present instance the fire extinguishing medium. Commonly, one of the foam-forming elements is water, and in the present instance I have illustrated the tank connected through a pipe 2 with a water main 3, the connection being controlled by a valve 4. The pipe 2 also preferably includes a suitable check valve (not shown) preventing a reverse flow through this pipe from the container or accumulator 1, and in the present instance an alarm device 5 connected to the pipe 2 is adapted to be actuated by water pressure in this pipe to close an electric circuit 6 including a suitable electric signal. Preferably the pipe 2 has associated therewith a drain 7 of a type including a ball float which permits escape of relatively small quantities of water leaking past the valve 4 but functioning to close the drain port when a large volume of water is admitted by the opening of the valve. The alarm and drain elements associated with the pipe 2 as set forth above may be of standard type, and form no essential part of the present invention.

80 The tank 1 normally contains a chemical element which reacts with the water entering the chamber through the pipe 2 to form a fire extinguishing foam, which latter accumulates in the tank 1 and escapes through a discharge pipe 8 located in the present instance at the bottom of the accumulator tank.

85 The valve 4, see Fig. 11, is of the differential type and comprises the valve proper 9 adapted to seat within the casing as illustrated to close the connection between the pipes 2 and 3. Extending upwardly from the valve 100

9 is a stem 11 having at the top a head 12 which bears against the under side of a diaphragm 13 secured as shown in the upper part of the casing. A spring 14 tends continuously to elevate the valve stem and with it the valve 9 from its seat.

The upper part of the valve casing above the diaphragm 13 is connected through a pipe 15 with a chamber 16 in a casing 17, in which chamber is operatively mounted a valve 18, said valve being adapted in alternate positions to close ports 19 and 21. The port 19 communicates with a cylindrical chamber 22, which chamber in turn communicates through a bypass channel 23 with a chamber 24 in a casing 25 integrally formed in the present instance with the casing 17, as illustrated in Fig. 7. Within the chamber 24 is mounted a valve 26 adapted to seat as illustrated in Fig. 5 so as to break the connection between the bypass 23 and a port 27, which through a pipe 28 is connected to a suitable drain.

The valves 18 and 26 are operatively connected by a stem 29 which projects through the walls of the casings 17 and 25 as illustrated in Figs. 2 and 5. With this stem 29, the valve 18 has a sliding connection, a spring 31 tending to force the valve away from the end of the stem and the relative movement of the valve with respect to the stem being limited by a shoulder 32, as clearly illustrated. This free movement between the stem 29 and the valve 18 insures the firm seating of the valve 18 in the alternative closing of the ports 19 and 21. Associated with the stem 29 within the chamber 22 is a spring 33 which exerts a pressure tending to force the valve 18 from its seat closing the port 19, as shown in Fig. 2, into the alternative position, as shown in Fig. 5, in which it closes the port 21. The stem 29 engages the valve 26 so as to hold this valve away from its seat when the valve 18 closes the port 19 and permits a spring 34 to seat the valve 26, as shown in Fig. 5, when the valve 18 is in the position closing the port 21. The connection between the stem 29 and the valve 26 is also a sliding one insuring a proper seating of the valve 26.

Intermediate the casings 17 and 25, the stem 29 comprises a threaded sleeve 30 which constitutes a means for adjusting the overall length of the stem and the relative positions of the end sections thereof, one end of this sleeve also functioning as a valve to close the opening in the casing 17 through which the stem extends, the valve being effective when the parts are as shown in Fig. 5.

The chamber 16 through the port 21 and a pipe 35 communicates with one or more sprinkler heads 36, see Fig. 1, of well known type which will be located within the area controlled by the fire extinguishing apparatus. The chamber 16 also is connected through the port 19 and through a pipe 37

extending from the chamber 22 with the bottom of a casing 38 mounted as illustrated in Fig. 1 at a point above the valve mechanism described above, this casing 38 being vented at the top, as indicated at 39 and functioning 70 in a manner and for a purpose hereinafter set forth.

In the present instance, the casing 38 is supported upon a pedestal 41 which is threaded into a casing 42, which casing has a port 43 communicating through a pipe 44 with the pipe 15, see Figs. 2 and 5, said casing 42 having a second port 45 which communicates through a pipe 46 with the water main 3. As shown in Fig. 1, this pipe 46 is controlled by 80 a valve 47. The casing 42 comprises chambers 48 and 51 which communicate respectively with the ports 43 and 45, and the chambers intercommunicate through a port 52 in which is established a stem 53 longitudinally 85 grooved or recessed in that part which projects through the port and adapted to restrict the opening to a desired extent. This stem 53 is supported in the inner end of a plug 54 threaded into the casing 42, the plug 90 having a recess 55 in the bottom of which the end of the stem 53 is held by a spring 56, this spring being held under compression by a plug 57 threaded into the outer end of said recess. The plug 54 also carries at its inner 95 end a cylindrical strainer 58 which surrounds the projecting portion of the stem 53 and whose outer end fits against the partition 59 in such manner as to completely surround the port 52. The strainer 58 prevents any foreign material in the water from clogging the restricted port 52.

From the foregoing description, it will be apparent that with the valve 18 closing the port 19, as it normally will, water from the main 3 will fill the pipe 46 and will pass through the restricted opening 52 into the pipe 15, and through this pipe to that portion of the valve casing 4 overlying the diaphragm 13 and also to the chamber 16 of the valve casing 17. The port 21 of this casing being open, water will also fill the pipe 35. Under these conditions, the valve 18 is held to its seat closing the port 19, and the main pressure upon the top of the diaphragm 13 of the differential valve 4 will also hold the valve 9 to its seat closing the pipe 2 and preventing passage of water from the main through said pipe to the accumulator 1. Also under these conditions, it will be noted that the valve 26 is open whereby the casing 38 is connected through the pipe 37 and the bypass 23 with the drain pipe 28.

Assuming now that the valve 18 is shifted to the alternative position, as shown in Fig. 5 closing the port 21, it will be apparent that the chamber 16 will be connected through the chamber 22 and pipe 37 with the casing 38, the valve 26 being closed and thereby disconnecting the chamber 22 from the drain. Also 130

the sleeve 30 now performs its valve function to prevent leakage from the chamber 22 around the valve stem 29. Opening of valve 18 results in a release of the pressure upon the top of the diaphragm 13 of the differential valve 4, which permits the spring 14 and the main pressure to elevate the valve 9 from its seat, thereby permitting a flow of water from the main 3 through the pipe 2 and into the accumulator 1. Influx of water into the accumulator results in generation of foam which discharges through the pipe 8 and is directed as required.

By reason of the restricted character of the port 52, water from the main 3 gradually fills the casing 38 until, when this casing is completely filled and by reason of the automatic closing of the vent 39 by a float valve (not shown), the main pressure is again restored in the pipe 15, and acting upon the diaphragm 13 closes the valve 9, preventing further flow of water from the main to the accumulator. The parts remain in this position until the valves 18 and 26 have been restored to their original positions, as may be done by means hereinafter set forth, whereupon the valve 18 is again held to its seat by the main pressure, closing the port 19, while the water in the casing 38 automatically escapes therefrom through the chamber 24 and the drain pipe 28, thereby restoring the apparatus to its original condition.

As previously stated, the chamber 16 is connected through the pipe 35 with one or more sprinkler heads 36, and it will be apparent that release of the sprinkler head by reason of excessive temperatures at the place of its location will result in a release of pressure in the chamber 16, permitting the spring 33 to shift the valve 18 over into the alternative position, as shown in Fig. 5. The sprinkler head or heads, therefore, constitutes one means for releasing the control valves of the aforescribed apparatus to permit the formation of the foam in the accumulator.

As shown in Fig. 2, I provide additional release means in the form of a release box 61, which in the present instance is carried upon a bracket 62, to which is secured the casings 17 and 25. Pivotal secured to this bracket 62 at 63 is a lever arm 64 which extends downwardly through the space between the casings 17 and 25 and is operatively connected with the stem 29 so that oscillation of the lever results in a corresponding longitudinal movement of the stem, and vice versa.

Pivotal secured at 65 to the bracket 62 is a lever 66, this lever having a transversely projecting lug 67 which when the lever turns about its pivot in a clockwise direction and as shown in Fig. 5 is adapted to engage the lower end of the lever 64. The upper end of the lever 66 is provided with weights 68 of such size that when the lever 66 is released

from the position shown in Fig. 2, as herein-after set forth, they will cause the extension 67 to strike the lever 64 with sufficient force to open the valve 18 against the water pressure which normally holds this valve to its seat closing the port 19.

The lever 66 is normally supported, as shown in Fig. 2, in an elevated position by a yoke 69 which passes over and engages an arm 71 of a bell crank lever 72 pivotally secured at 73 to the front of the box 61. The other arm of the bell crank lever 72 extends upwardly as shown in Fig. 2 and turns inwardly and downwardly through an opening 74 in the front cover of the box 61 to be engaged and normally held in the upright position, as shown, supporting the weight 68 by a latch 75 in the form of a suitably shaped arm of a bell crank lever 76 pivotally mounted at 77 within the box 61. The other arm 78 of this lever 76 extends downwardly in the box, and its lower end is normally engaged by an arm 79 of a second pivoted lever 81 in the bottom of the box to prevent oscillation of the lever 76 in a clockwise direction, see Fig. 2, to an extent releasing the arm 72. The lever 81 has a second arm 82 which extends upwardly and engages a shoulder 83 upon a lever 84 pivotally mounted at 85 in the casing and projecting inwardly to hook under a transverse piece 86 on a latch 87 pivotally mounted at 88 in the casing, the lever 84 being normally prevented from upward oscillation by this latch 87. A spring 89 attached to the upper end of the latch resiliently holds the latter in an advanced position such that the part 86 overlies the inner end of the lever 84.

The lower end of the latch 87 engages behind the head 91 of a pin 92 which is secured to a diaphragm 93 secured as illustrated over a dished receptacle 94, this receptacle having a port from which a small pipe 95 extends through the side of the casing 61. Under atmospheric pressure within the receptacle 94, the diaphragm 93 occupies the position shown in Fig. 2, which permits the latch 87 under the action of the spring 89 to assume a position in which the lever 84 engages under the latch part 86, as described above and as illustrated in the aforesaid Figure 2. When the receptacle 94 is evacuated, as by means hereinafter described, the diaphragm 93 will be flexed inwardly, as shown in Fig. 5, and will thereby through the pin 92 oscillate the latch 87 to an extent releasing the arm 84. Release of the arm 84 in this manner results in a release of the arm 82, and the lever 81 is thereby permitted to oscillate inwardly to release the arm 78. The lever 76 is adapted to swing inwardly so as to release the arm 72 of the lever 73, which latter swings outwardly and releases the weight 68 and the lever 66. In the downward movement of the latter, the transverse projection 67 en-

gages the forward edge of the lever 64 with sufficient force acting through the stem 29 to open the valve 18, with the results described above. It will be noted that in addition to the action of the weight 68 tending to oscillate the lever 71-72 outwardly from the casing, the arm 72 of this lever is engaged by a spring-pressed plunger 96 in the casing, which tends to force the arm away from the casing and to release it from the latch arm 75.

The parts of the release mechanism in the released condition are shown in Fig. 5. It will be noted that a pin 97 is provided for supporting the lever arm 84 in a substantially horizontal position, and that the inward movement of the lever 81 is limited by engagement of the arm 79 with the partition stop 98. Also a pivoted stop 99 is provided in the top of the casing which by engaging the latch arm 75 prevents forward oscillation of the lever 76 after the rearward oscillation which releases the arm 72. An aperture 101 is provided in the cover plate of the casing 61 whereby this stop 99 may be forced inwardly to release the arm 75 to permit the lever 76 to return to the normal position, as shown in Fig. 2, and a spring 102 is provided which normally tends to return the lever to this position.

In resetting the parts to their original unsprung condition, the arm 72 is elevated, the weighted yoke 69 having been attached to the arm 71 and the upper curved hook end of the lever 72 forced inwardly through the aperture 74 and over the latch arm 75. The extremity of the arm 72 first engages the stop 99 and forces the latter inwardly, thereby releasing the arm 75, it being apparent that this latter arm cannot be elevated and the parts returned to their original positions until this lock 99 has been displaced. With the arm 72 in position as shown, the lever 81 may be oscillated in a clockwise direction by means of a knob 103 exterior of the casing 61 which through a shaft 104 is connected with this latter lever. The arm 82 in moving outwardly engages the under side of the lever 84 and must displace this lever upwardly in order to clear the shoulder 83 which normally holds the arm 82 in the advanced position. This displacement is provided for in the slotted formation of the pivot hole, and a spring 90 is provided to normally hold the lever in a depressed position at the pivot. The setting of the trip mechanism is completed by restoration of normal atmospheric pressure to the chamber 94, as by means hereinafter set forth, which results in a return movement of the diaphragm 93 to the normal position shown in Fig. 2 and permits the spring 89 to return the lever 87 to a position in which the cross piece 86 is effective to prevent elevation of the outer extremity of the lever 84.

It will be noted that I have provided with-

in the casing a bell crank lever 105 the upper end of which is in position to engage the end of the diaphragm pin 92, this bell crank lever 105 being connected through a link 106 with the upper end of the valve controlled lever 64. Under normal conditions, the lever 105 occupies the position shown in Fig. 2. When the valve 18 moves over into the alternative position, however, as shown in Fig. 5 and as occurs for example when the normal fluid pressure in the chamber 16 is relieved by the opening of one or more of the sprinkler heads 36, the accompanying movement of the stem 29 acting through the lever 64 and link 106 oscillates the lever 105 into contact with the pin 92 flexing the diaphragm 93 inwardly and thereby releasing the trip mechanism and permitting the lever 72 to drop.

In resetting the apparatus after actuation through the medium of the sprinkler heads 36 as explained, it is necessary to withdraw the valve stem 29 and the associated parts into the positions shown in Fig. 2, and to hold these parts in the retracted position until sufficient fluid pressure has been built up in the chamber 16 to offset the pressure of the spring 33 tending to advance the stem. Actuation of the trip mechanism prevents the possible overlooking of this essential resetting operation, since the released position of the weights is an inescapable indication that the mechanism is not in operating condition. Proper complete resetting is thus assured.

Evacuation of the receptacle 94 as described above is accomplished in the present instance through the medium of a thermosensitive device illustrated in Figs. 9 and 10. This device comprises a casing 111 in which is established an expansible element or sylphon 112. This sylphon is supported between a shoulder 113 in the top of the casing and a threaded closure member 114. This closure has a port 115 which communicates with the interior of the sylphon and is controlled in the present instance by a gravity-actuated check valve 116 which permits air to pass from the interior of the sylphon but prevents a return flow of air through said port. The closure 114 also has a port 117 which also communicates with the interior of the sylphon and through the pipe 95 with the chamber 94 of the trip mechanism.

In the interior of the sylphon 112 and reacting against the inner face of the closure member 114 is a spring 118 which tends to extend the sylphon from the normal contracted position in which it is shown in Fig. 10. In the present instance, the bottom of the sylphon is recessed at 119, and in this recess is established a stem 121 which projects downwardly through a passage 122 in the threaded body portion 123 of a thermosensitive release unit. The lower end of the passage 122 is normally stopped by a closure

member 124 which is held to a seat on the body member 123 by a pair of strut members 125, the upper ends of which bear against the outer face of the closure member 124, 5 while the lower ends are braced respectively against the outer ends of a pair of levers 126. These levers 126 are engaged behind the inwardly beaded lower edge 127 of the body member 123, while the levers converge to 10 bear against the upper face of a washer 128 which is slidably mounted upon a stem 129 extending downwardly from the closure 124. The washer 128 is normally held in an elevated operative position with respect to the 15 levers 126 by a body of fusible compound 131 which is confined between the washer 128, a head 132 on the extremity of the stem 129, and a cylindrical cover member 133 which embraces the head 132 and a portion of the 20 washer 128.

In operation fusion of the compound 131 permits the sleeve 128 to slide outwardly on the stem 129, thereby releasing the inner ends of the levers 126. The struts 125 are therefore 25 released so that the entire closure member drops away to release the stem 121, thereby permitting the spring 118 to extend the sleeve, which results in an evacuation through the pipe 95 of the chamber 94 of the 30 trip mechanism. In resetting the latter mechanism, the sylphon is contracted and the struts 125 and the thermosensitive release element restored to its original condition to thereby support the sylphon in the contracted 35 position. In the contractive movement of the sylphon, it is apparent that any excess air in the system will be expelled through the port 115.

The operation of the apparatus as a whole 40 will be apparent from the foregoing description.

I claim:

1. A fluid system comprising a main duct, a differential pressure valve controlling said duct, a branch duct providing main pressure at the valve normally retaining it closed, and means for relieving and subsequently restoring the pressure in said branch duct including a timing chamber connected with 45 said branch duct and having an independent drain, a second valve interposed and directly controlling the connection between the branch duct and the said chamber and normally retained in the closed position by the main pressure in said branch duct, and a third valve controlling the said drain and having a synchronized operative connection with said second valve whereby when the latter valve is closed the drain valve is opened, 50 and vice versa.

2. A fluid system comprising a main duct, a branch duct, and a timing chamber connected with said branch duct and having an independent drain, of a differential pressure valve controlling said main duct and opera-

tively associated with said branch duct whereby main pressure in the latter duct normally maintains the valve closed, a second valve interposed between said chamber and the branch duct, said valve being also normally maintained in the closed position by the main pressure in said branch duct and directly controlling the connection between the branch duct and the timing chamber, means for closing said second valve, a third 70 valve controlling the drain from said timing chamber and operatively connected with said second valve whereby the opening of said second valve is effective to close the third valve and whereby the third valve is opened 75 when the second valve is closed, and means for effecting the opening of said second valve.

3. A fluid system comprising a main duct adapted for connection with a source of fluid supply, a differential pressure valve controlling said duct, a timing chamber, a branch duct connecting the timing chamber with the main duct and also connected with said valve whereby the main pressure is effective to normally retain the valve closed, 80 a second valve controlling the connection between the branch duct and the timing chamber and also normally retained closed by said main pressure, a single restriction in said branch duct effecting the 85 flow from the main duct to both of said valves and to the timing chamber, means for effecting the opening of the second valve, an independent drain for said timing chamber, a third valve operatively connected with 90 said second valve and controlling said drain, means for closing the said third valve by the opening movement of the second valve, and means for restoring said second valve to its 95 seat and for simultaneously opening the third 100 valve to permit said timing chamber to drain.

4. A fluid system comprising a pressure duct, a container, a valve casing having a chamber connected with said pressure duct, and a second chamber connected with said container, and a port providing communication between said chambers, valve means controlling the said port including a stem projecting through the wall of said second chamber, said stem comprising a part effective to 110 seal the opening in said second chamber through which the stem projects, and means for shifting the stem to open the valve and simultaneously to bring said sealing part into 115 operative position with respect to said opening.

5. In a fluid system, the combination with a pressure duct, of a container, a valve casing having a chamber connected with said pressure duct, and a second chamber connected 120 with said container, and a port connecting said chambers, a valve controlling the connection between said chambers and adapted normally to be held closed by the pressure in said duct, a valve-actuating stem projecting 125

through the wall of said second chamber and having a part adapted to seal the opening in said second chamber through which the stem projects, means for actuating said stem to open the valve and to seal said opening upon relief of the closing pressure, thermosensitive means for relieving said pressure, means for actuating said stem to open the valve against the closing pressure including thermosensitive trip mechanism, and an operative connection between the valve stem and the trip mechanism whereby actuation of the stem by relief of said pressure results in a release of the said trip mechanism and operation of said second stem actuating means.

6. A fluid system comprising a pressure duct, a pair of ports communicating with said duct, a valve adapted in alternative positions to individually close said ports and adapted normally to be held to a seat closing one of said ports by the pressure in said duct, a thermally-actuated valve normally preventing flow through the other of said ports and adapted when open to relieve the pressure in the duct, and means operative upon relief of said pressure to shift the first-named valve from its normal seat to the alternative position closing the other port.

7. A fluid system comprising a pressure duct, a pair of ports communicating with said duct, a valve adapted in alternative positions to individually close said ports and adapted normally to be held to a seat closing one of said ports by the pressure in said duct, a thermally-actuated valve normally preventing flow through the other of said ports and adapted when open to relieve the pressure in the duct, and means for shifting the first-named valve from its normal seat to the alternative position closing the other port.

8. In a fluid system, the combination with a pressure duct, of a container, a valve casing having a chamber connected with said pressure duct, a second chamber connected with said container, and a port connecting said chambers, a valve controlling the connection between said chambers and adapted normally to be held closed by the pressure in said duct, a valve-actuating stem projecting through the wall of said second chamber and having a part adapted to seal the opening in said second chamber through which the stem projects, means for actuating said stem to open the valve and to seal said opening upon relief of the closing pressure, means for relieving said pressure, means for actuating said stem to open the valve against the closing pressure including thermosensitive trip mechanism, and an operative connection between the valve stem and the trip mechanism whereby actuation of the stem by relief of said pressure results in a release of said trip mechanism and operation of said second stem-actuating means.

9. In a fluid system, the combination with

a pressure duct, of a container, a valve casing having a chamber connected with said pressure duct, a second chamber connected with said container, and a port connecting said chambers, a valve controlling the connection between said chambers and adapted normally to be held closed by the pressure in said duct, a valve-actuating stem projecting through the wall of said second chamber, means for actuating said stem to open the valve upon relief of the closing pressure, thermosensitive means for relieving said pressure, means for actuating said stem to open the valve against the closing pressure including thermosensitive trip mechanism, and an operative connection between the projecting portion of said valve stem and the trip mechanism whereby actuation of the stem by relief of said pressure results in a release of the said trip mechanism and operation of the said second stem-actuating means.

10. In a fluid system, the combination with a pressure duct having a pair of ports, of a valve normally held in position closing one of said ports by the pressure in said duct and movable into an alternative position closing the other of said ports, a second valve normally preventing flow through the last-named port and adapted when open to relieve the pressure in the duct, means for moving the first-named valve from its normal position to the alternative position when pressure in the duct is relieved by the opening of said second valve, means including trip mechanism and operative to unseat the first-named valve against the duct pressure, and means operatively connecting the first-named valve with the trip mechanism whereby the unseating of the valve by the valve-actuating means first named results automatically in actuation of the trip mechanism and release of the second valve-actuating means.

ARTHUR C. ROWLEY.
